LINE TRACER INSTRUMENT

Arthur F. Dean, Glenview, and Anton J. Panzica, Hinsdale, Ill., assignors to Stewart-Warner Corporation, Chicago, Ill., a corporation of Virginia

Filed Dec. 23, 1960, Ser. No. 63,319

Term of patent 14 years

(Cl. D52—6)

FIG. 1.

FIG. 2.

FIG. 3.

FIG. 4.

FIG. 1 is a perspective view taken from the front and to one side of a line tracer instrument, embodying our new design;

FIG. 2 is an elevational view of the front of the line tracer instrument;

FIG. 3 is a side elevational view showing the right side of the line tracer instrument;

FIG. 4 is a plan view showing the top of the line tracer instrument.

The rear of the line tracer instrument is substantially plain except for the elements shown in dotted lines. The dominant features of our design reside in the portions shown in full lines in the figures. Portions of the instrument are stippled to indicate color contrast.

We claim:

The ornamental design for a line tracer instrument, substantially as shown and described.
